(57) **CLAIM**

The ornamental design for a shim with frangible portions, as shown and described.

DESCRIPTION

FIG. 1 is a rear perspective view of a shim with frangible portions showing our new design;

FIG. 2 is a front elevational view thereof;

FIG. 3 is a left side elevational view thereof, the right side elevational view being a mirror image thereof;

FIG. 4 is a top plan view thereof; and,

FIG. 5 is a bottom plan view thereof.
